UNITED STATES PATENT OFFICE.

REGINALD G. STANDERWICK, OF LYNN, MASSACHUSETTS, ASSIGNOR TO GENERAL ELECTRIC COMPANY, A CORPORATION OF NEW YORK.

DISTRIBUTION SYSTEM FOR VAPOR ELECTRIC DEVICES.

1,093,083.

Specification of Letters Patent. Patented Apr. 14, 1914.

Application filed May 24, 1913. Serial No. 769,599.

To all whom it may concern:

Be it known that I, REGINALD G. STANDERWICK, a subject of the King of Great Britain, residing at Lynn, county of Essex, State of Massachusetts, have invented certain new and useful Improvements in Distribution Systems for Vapor Electric Devices, of which the following is a specification.

The present invention relates to the operation and regulation of vapor electric devices, particularly the operation of alternating current vapor lamps, or the like, on variable voltage circuits.

My invention is particularly applicable to what is known as the high pressure lamp, which is operated in a refractory envelop, such, for example, as quartz.

The "high pressure lamp," also commonly known as the "quartz lamp," is quite distinct in its electrical characteristics from a low pressure lamp, commonly operated in a long glass envelop. One of the best distinctions that may be drawn between these two types of lamps is the following: A low pressure, low temperature vapor lamp takes about the same voltage and consumes about the same amount of energy at starting as it does in normal operation, while a high pressure lamp starts at considerably lower voltage and at starting takes less energy than under normal operating conditions when the lamp has come to a final equilibrium. The energy consumption in a high pressure lamp is considerably greater per unit length than in a low pressure lamp, and it may be said that the high pressure lamp as now commonly constructed and proportioned operates with a consumption of more than 25 watts per inch in a tube about $\frac{1}{2}$ " in diameter. In other words, more than about 15 watts per square inch of surface. In fact, the usual energy consumption is about 80 to 100 watts per inch length in a tube of this diameter. The character of the high pressure lamp has been described to distinguish it from the low pressure lamp from which it differs materially in many respects particularly in the relation of voltage to current.

It is the main object of the present invention to provide an electrical system of distribution in which an alternating vapor device of the high pressure type may be operated with the greatest economy and stability, while also safe-guarding the device itself against overvoltage. In accordance with my

invention a vapor electric device is operated from a source of alternating current such as a transformer having a core operated at such magnetic saturation that an increase of voltage will be accompanied by a more than corresponding decrease of current, thus resulting in a decrease of wattage in the energy consumed.

Figure 1 illustrates a vapor electric device connected in a constant current variable voltage series circuit in accordance with my invention; Fig. 2 illustrates by curves the voltage and current relations in high pressure vapor electric devices; Fig. 3 is a detail sectional view of the cathode end of the device showing the mercury electrode.

Fig. 1 shows a series circuit 1 supplied by a constant current transformer 2 having as usual a stationary primary coil 3 and a movable secondary coil 4. In this circuit are primaries of series transformers 5, 6, complete connections to only one of which have been shown in detail for purposes of illustration, but it should be understood that any number of devices may be similarly operated in series. The transformers 5 and 6 have been somewhat diagrammatically indicated as being of the compensator type in which the primary and secondary coils are not separate and distinct but one is a continuation of the other. My invention also is applicable to other forms of transformer devices. To the secondary 7 of transformer 5 is shown connected a mercury vapor lamp 8, the anodes 9 and 10 consisting of refractory material, preferably tungsten, and being connected to the terminals of the secondary winding by means of conductors 11 and 12. The cathode 13 consists of mercury, or other easily vaporizable materials, and is connected to a point of intermediate potential, by conductor 14 including preferably an inductance 15. An arc is started by tilting as usual.

The transformers 5 and 6 are provided with iron cores 16 and 17 proportioned to operate near saturation as will be described. When a high pressure device, provided with a mercury anode as described, for example, by Kuch Patents 793,530 and 883,725, and having some anode condensing means, such as fins or a cooling chamber, is placed on a series or constant current circuit, it has a volt ampere characteristic as illustrated by curve A of Fig. 2. In this curve the value

2

of current and voltage are plotted respectively as abscissa and ordinate in a lamp of a given length of tube. It will be noted that at a certain critical current value that the 5 curve is almost perpendicular. If it were attempted to operate such a lamp on an ordinary series circuit, at the critical current value, the voltage would rise continuously until the wattage increased to a point sufficient to destroy the lamp. This general 10 shape of the volt-ampere curve is also characteristic of a vapor device in which the anode consists of solid material, but as shown by curve B continues its critical rise 15 to a higher limit of current. The curve may be still more flattened by providing some condensing means near the cathode as disclosed in application Serial No. 753,947, filed March 13, 1913, by Ezechiel Weintraub, 20 but as shown by curve C it also becomes steep at a higher current value. If any of these types of higher pressure vapor devices were operated without special provisions being made, on a variable voltage 25 constant current circuit it would be necessary to limit the current materially below the critical point at which the curve becomes very steep. As the general shape of the volt-ampere curve is affected by the amount 30 of cooling and other variable factors, it is not entirely safe to depend upon the characteristic of the circuit and the current limit set by the constant current transformer, or other source of energy. As a lamp 35 of the high pressure type is operated at the greatest efficiency at higher current values it is desirable that a lamp of this type should be operated as near as possible to the point at which the voltage begins to rise abruptly 40 without further increase of current. Therefore, if any change of external conditions or of the electrical characteristic of the circuit should take place the lamp would be endangered. When in accordance with my 45 invention the lamp, rectifier or other device is connected to a supply device proportioned to operate at a flux density corresponding substantially to the maximum wattage, any 50 incipient rise of voltage will produce a decrease of wattage thus restoring the lamp to normal operating conditions and preventing injury by over-heating.

While I have illustrated diagrammati-

cally in Fig. 1 a mercury vapor lamp having solid anodes connected to a transforming device proportioned in accordance with my invention, I wish it to be understood that other types of high pressure devices, such as rectifiers, and also devices having mercury anodes, and provided with special cooling means may be similarly operated.

My invention enables an alternating current high pressure lamp to be operated on series circuits with simple connections and a simple starting mechanism at higher efficiency than a high pressure lamp of the same rating operated on direct current circuits, as a series steadyng resistance is not required.

What I claim as new and desire to secure 70 by Letters Patent of the United States, is,—

1. The combination of a high pressure vapor electric device having a cathode and a plurality of anodes, and an alternating current supply means therefor, proportioned to operate at a flux density corresponding substantially to the maximum wattage output, whereby an increase of voltage will be accompanied by a decrease of current. 80

2. The combination of a constant current variable voltage line, a transforming device having its primary connected in series therewith, a vapor electric device having anodes connected to the secondary terminals of said 85 device and a cathode connected to a point of intermediate potential on said secondary, the transforming device being proportioned with respect to the vapor device to operate near its maximum wattage output. 90

3. The combination of a high pressure alternating current mercury lamp, and a transforming device supplying electrical energy thereto, said device having a magnetic core proportioned to operate so near 95 to saturation that an increase of the secondary voltage will be accompanied by a correspondingly greater decrease of the secondary current.

In witness whereof, I have hereunto set 100 my hand this 8th day of May, 1913.

REGINALD G. STANDERWICK.
